No. 836,439.

PATENTED NOV. 20, 1906.

I. W. COLBURN.

PROCESS AND APPARATUS FOR DRAWING SHEET GLASS.

APPLICATION FILED JULY 10, 1906.

6 SHEETS—SHEET 1.

Witnesses

Fransich A. Holton.

Sustene R. Thompson.

UNITED STATES PATENT OFFICE.

IRVING W. COLBURN, OF FRANKLIN, PENNSYLVANIA.

PROCESS AND APPARATUS FOR DRAWING SHEET-GLASS.

No. 836,439.

Specification of Letters Patent.

Patented Nov. 20, 1906.

Application filed July 10, 1906. Serial No. 326,543.

To all whom it may concern:

Be it known that I, IRVING W. COLBURN, of Franklin, Pennsylvania, have invented a new and useful Improvement in Processes and Apparatus for Drawing Sheet-Glass, which improvement is fully set forth in the following specification.

This invention relates to the art of drawing sheet-glass, and is applicable to the drawing of sheets of fixed length, as well as to the continuous drawing of the glass in sheet form.

When an effort is made to draw a sheet of glass from a mass of molten glass, one of the great difficulties to be overcome is the tendency of the started sheet to rapidly narrow to a string or cord. Another difficulty lies in the fact that it is extremely difficult to avoid the formation of wave-like lines or striæ upon the faces or surfaces of the sheet of glass as it is drawn, which lines or striæ very materially injure the market value of the glass and, in fact, render it practically unfit for a great variety of uses. A further difficulty experienced in the drawing of sheet-glass, and particularly in the drawing of a continuous sheet, lies in the fact that the mechanism employed in handling the sheet, especially at a time when the sheet is at all softened by the influence of heat, must move in absolute union with the movements of the sheet at all times, to the end that there may be no slipping action or relative movement between any portions of the mechanism and the surface of the sheet with which such mechanism may be in contact, since such slipping action or relative movement between the two surfaces would be liable to slightly mar the finish of the glass.

The object of the present invention is to provide a method and means whereby a sheet of glass of uniform width can be drawn from a mass of molten glass and whereby the formation of wave-like lines or striæ upon the surfaces of the sheet, as well as the marring effect due to contact with any of the mechanism, may be avoided.

In previous applications filed by myself and Edgar Washburn as joint inventors, said applications being Serial No. 248,288, filed March 3, 1905, and Serial No. 304,555, filed March 6, 1906, there is disclosed a method and apparatus for overcoming the narrowing tendency of the sheet during the drawing operation, which method, generally stated, con-

sists in imparting to the surface portion of the molten mass during the operation of drawing a sheet lateral movement in opposite directions and away from the two edges of the sheet. This is accomplished by immersing moving bodies, such as revolving spheres, in the molten mass adjacent to the edges of the sheet being drawn and revolving them in such a direction that their adjacent surfaces move upward and outward.

The formation of ribs or striæ upon the surface of the drawn sheet of glass may be and probably is due to a variety of causes. Among these may be mentioned the tendency of the surface of the molten glass in the working chamber or pot when the same is exposed to the cooling influences of the external atmosphere to take or receive impressions from the roughened side walls of the working chamber or pot. This is particularly true if the point where the molten glass leaves the walls or other part of the receptacle be but a few inches from the point where the glass enters the sheet. Moreover, the chilling influence of the atmosphere itself is liable to cause the surface of the molten glass to more or less wrinkle or form into minute waves or ridges. These are some, though doubtless not all, of the causes of the formation of ribs or striæ upon the surfaces of the sheet. Now during the operation of drawing a sheet of glass the tendency of the surface portion of the molten mass in the working chamber or pot is to move slowly toward and into the sheet being drawn, so that any wave-like lines upon the surface of the molten mass would ultimately appear in the surface of the drawn sheet in the form of ribs or striæ.

I have discovered that if during the operation of drawing a sheet of glass from the molten mass a part of the surface portion of the molten mass has movement imparted to it in opposite directions and away from the two faces of the sheet being drawn the formation of the ribs or striæ in the surfaces of the drawn sheet are avoided. Moreover, I have discovered that it is also desirable in order to avoid the formation of such ribs or striæ the surface portion of the molten mass at a point remote from the sheet being drawn in the working chamber or pot should be heated to a degree above that which it is desired the surface of the mass shall possess at the time when it enters the sheet and

only a limited area of the surface of the molten mass should be exposed to the cooling influences of the atmosphere at or adjacent to the point where the sheet is being drawn.

- 5 By thus raising the temperature of those portions of the molten mass somewhat remote from the sheet being drawn and by regulating the area of the surface of the molten mass exposed to the cooling influences of the 10 atmosphere it becomes possible to present the glass to the formative point at a proper temperature and in the proper condition for drawing into a sheet without the formation of the objectionable ribs or striæ, and when 15 this step is performed in conjunction with that of imparting movement in opposite directions to a part of the surface portion of the mass away from the two faces of the sheet being drawn the sheet will be perfectly 20 free from such ribs or striæ.

One part of the invention in the present instance, therefore, resides in a method of drawing a sheet of glass from a mass of molten glass and simultaneously imparting 25 movement to a part of the surface of the molten mass away from the two faces of the sheet being drawn, and, furthermore, the invention resides in a method of superheating portions of the molten mass remote from the 30

- 35 point where the sheet is being drawn and then limiting the area of the molten mass exposed to the cooling influences of the atmosphere. Preferably each of the above-mentioned steps are practiced jointly—that is, motion is imparted to a part of the surface of the molten mass in opposite directions and away from the two faces of the sheet being drawn, while at the same time remote portions of the molten mass are superheated 40 and the area of the molten mass exposed to the cooling influences of the atmosphere is controlled within the desired limits. By "superheated" as herein employed is meant the heating of the surface portion of the 45 mass to a degree above that which it is desired the glass should have at the time when it assumes sheet form or at the time when it passes from the molten mass into the form of a sheet. As one of the essential steps in 50 drawing the sheet of glass the method also includes holding the sheet to uniform width in any effective way, as by imparting movement to the surface portion of the molten mass near the sheet's edges in a direction 55 away from the medial line of the sheet and toward the edges of the sheet during the drawing operation.

For the purpose of imparting movement to the surface portion of the molten mass 60 away from the surfaces or faces of the sheet during the drawing operation I preferably employ two refractory rollers, with the lower portion of their peripheries immersed in the surface of the molten mass in the working chamber or pot, and slowly revolve these roll-

ers in opposite directions during the operation of drawing the sheet of glass from the molten mass lying between the rollers. Preferably, though not necessarily, the two rollers are revolved in opposite directions with their adjacent surfaces moving upward. They may be revolved, however, with their adjacent surfaces moving downward. The use of such rollers serves not only to impart movement to a part of the 75 surface of the molten mass away from the faces of the sheet during the drawing operation, but serves also to determine the area of the surface of the molten mass in the working chamber or pot which is more or less exposed to the cooling influences of the atmosphere, and the superheating referred to above occurs on that portion of the surface of the molten mass to the rear of said rollers—that is, on the sides of said rollers away from the sheet 80 being drawn. This superheating may be accomplished in any suitable manner, as by directing heated gases of combustion against the glass and rollers on the rear side of said rollers.

For the purpose of holding the sheet to its uniform width I may employ bodies of refractory material immersed in the molten mass adjacent to the edges of the sheet being drawn therefrom and moving in such a manner as to impart an outward motion to that portion of the surface of the molten mass lying immediately adjacent to the edges of the sheet. These bodies for holding the glass to its uniform width may be of any suitable 95 construction, such as revolving spheres shown in the joint application of myself and Edgar Washburn, Serial No. 238,592, filed December 28, 1904, or they may be in the form of hooks of refractory material, such as 100 shown in the joint application of myself and Edgar Washburn, Serial No. 304,555, filed March 6, 1906.

If a sheet of glass be drawn from the molten mass lying between the rollers aforementioned and means be employed to impart an outward movement to that portion of the surface of the molten mass lying immediately adjacent to the edges of the sheet, the following action of the molten glass will be observed: The molten glass at and just beneath the surface adjacent to the edges of the sheet will move away from the center line of the sheet—that is, outward—thus serving to hold the sheet to its full width. As the sheet of glass moves upward there is drawn into the sheet some of the surface portion of the molten mass immediately adjacent to the two faces of the sheet and also some of the molten glass beneath the surface. At the same time 115 the two rollers on the opposite sides of the sheet of glass also serve to draw some of the surface portion of the molten mass lying between the rollers and the sheet of glass away from the sheet. It will thus be seen that the 120

125 130 135

result of the combined action of the drawing of the sheet and the movement of the rollers is the "skimming," as it might be called, of the surface portion of the molten glass lying between the two rollers, thereby exposing a fresh portion or a new surface of molten glass to the cooling effect of the atmosphere. This action is continuous, and the result is a continuous supply of fresh glass to the surface, which in turn is submitted to the cooling action of the atmosphere before it passes into the sheet. A further action of the rollers is to bring a supply of fresh hot glass into the area lying between the rollers and the sheet being drawn. The glass which is skimmed from the surface by the rollers and carried over by the rollers is subjected to the super-heating action at the rear of the rollers and is melted down, so as to free the rollers from the mass of glass clinging thereto and place such glass in proper working condition. The slow movement of the rollers, hereinafter referred to, affords ample time for this melting down of the glass carried over by the rollers.

In order to secure the desired results, it is necessary that the speed with which the sheet of glass is drawn and the speed with which the rollers are revolved should be properly regulated. This can be determined by experience and will vary with the conditions of each particular case, depending upon the temperature of the molten mass in the working chamber or pot, the temperature of the external atmosphere, the thickness of the sheet to be drawn, &c. Generally speaking, the speed at which the sheet is drawn will vary from six to thirty inches per minute, and the revolution of the rollers will vary from one revolution in ten minutes to one revolution in thirty minutes, and for this purpose there is of course introduced into the machine suitable mechanism for adjusting the speed of draft of the sheet and speed of the rollers. It will thus be observed that there occurs a continuous skimming of the entire surface of the working chamber between the rollers, and as this skimming action occurs fresh glass continuously comes up from below at some point between the sheet and the roller, which in turn affords a new surface to be subjected to the cooling influence of the atmosphere, which is in turn skimmed and passed into the sheet. This action is the same between each roller and the sheet being drawn. In other words, fresh glass is coming up from below at two places—one between each roller and the sheet. The skin or the surface of the molten mass becomes the skin or surface of the sheet being drawn, and it is this skin or surface that must be kept free from the ribs or striæ.

It will be understood that in the action above described all of the various steps are proceeding simultaneously—that is, glass is

being drawn from the surface by the moving sheet and by the rollers and fresh glass is coming up to form a new surface, all of these proceeding simultaneously. Of course the sheet of glass being drawn and the rollers affect not only the immediate surface portion of the molten mass, but also act to draw glass that is beneath the immediate surface, the rollers also bringing hot glass to the working part of the pot between the rollers. Moreover, this supply of hot glass keeps the temperatures even and allows an even thickness of glass to be drawn. This furnishing of a new supply of hot glass from the back of the rollers to the surface portion of the mass between the rollers is one of the important functions of the rollers. By revolving the rollers at the slow rate mentioned above ample time is afforded to melt the glass from the rear sides of the rollers, and, moreover, this slow movement avoids the possibility of air-bubbles being carried down by the rollers into the molten glass. This is important, as the presence of such bubbles would result in blisters on or in the drawn sheet of glass.

In the continuous production of sheet-glass the most convenient means for handling the sheet consists of an apparatus for drawing the sheet vertically and then turning it from a vertical to a horizontal position, the turning being made over a suitable bending-roller, which is positively driven so as to revolve in the same direction in which the sheet of glass is moving and is intended to revolve at the same rate of speed as the sheet moves, to the end that there may be no relative movement between the surfaces of the roller and of the sheet of glass. In practical operation, however, it has been found almost impossible to insure at all times the uniform movement of the surface of a positively-driven roller and the sheet of glass. While the two could usually be relied upon to move synchronously, nevertheless there would at times occur certain relative movements between the two surfaces which would result in a slight marring of the fire-finish upon the glass. If the movements of the roller are made to depend upon the movements of the sheet of glass, this relative movement between the roller and the sheet will be entirely obviated and the marring action due to such relative movement avoided. In some cases this may be accomplished by mounting the bending-roller as an idler-roller on antifrictional bearings and causing it to be revolved slowly by the frictional contact of the moving sheet of glass, as shown, described, and claimed in the aforesaid application Serial No. 304,555. I have found, however, that in many instances the weight of the roller is so great and the conditions under which the glass is drawn vary to so great an extent that it is desirable to utilize some positively-driven mechanism in driving the

roller and at the same time control the revolution entirely by the movement of the sheet of glass.

Generally stated, therefore, my invention 5 consists:

First. In a method of drawing a sheet of glass by preparing a molten mass of glass, drawing a sheet therefrom, and simultaneously imparting movement to a part of the 10 surface portion of the molten mass in opposite directions and away from the faces of the sheet during the drawing operation.

Second. The invention consists in superheating the surface portion of the molten 15 mass remote from the sheet being drawn, restricting the area of the surface portion of the mass adjacent to the sheet being drawn and exposed to the external atmosphere, and preferably submerging the surface portion of 20 the molten mass as it passes from the superheated to said restricted area.

Preferably the methods defined in the first and second paragraphs will be practiced in conjunction with the additional step of imparting lateral movement to the surface portion 25 of the molten mass away from the edges of the sheet during the drawing operation, though some other means for holding the sheet to uniform width may be employed, if 30 desired.

Third. The invention consists in means for drawing a sheet of glass from a mass of molten glass, combined with means for imparting movement to the surface portion of 35 the mass in opposite directions and away from the faces of the sheet being drawn. Preferably the means for thus imparting motion to the surface of the molten mass consist of a pair of parallel refractory rollers having 40 their peripheries partially immersed in the molten mass and revolving in opposite directions, the sheet being drawn from the molten mass lying between the rollers. I prefer to have the rollers revolve so that their 45 adjacent surfaces move upward and outward, though they may in some cases be revolved in the opposite direction.

Fourth. The invention consists in means for superheating the surface portion of the 50 molten mass remote from the sheet being drawn, combined with means located between such superheated portion and the point where the sheet is drawn, which means act to submerge the surface portion of the 55 molten mass and to limit the area of the molten mass which is exposed to the cooling influences of the external atmosphere. The means for superheating the remote portions of the mass may consist of any means for 60 supplying gases of combustion at a high temperature to the surface of the molten mass—such, for example, as suitably-constructed burners. Preferably the means for submerging the surface of the mass at a point 65 between the superheated portion and the

point of the sheet and also the means for limiting the area of the molten mass exposed to the cooling influences of the atmosphere may be one and the same structure and may also be identical with the means for imparting 70 movement to a part of the surface portion of the mass in opposite directions and away from the faces of the sheet during the drawing operation, and as here shown these three sets of means are all combined in one 75 and are illustrated in the shape of a pair of refractory rollers having their peripheries partially immersed in the molten mass and revolving in opposite directions.

Fifth. The invention consists in a bending- 80 roller over which the sheet of glass is bent or turned during the drawing operation, which roller receives the power necessary to set it in motion from the frictional contact of the sheet of glass acting in conjunction with positive power mechanism. Usually bending-rollers of the character referred to are quite heavy, weighing considerably more than half a ton. If such rollers are mounted on delicate antifrictional bearings, as described 85 in the aforementioned application Serial No. 304,555, the frictional contact of the sheet in most cases will be sufficient to impart revolution to the roller, which revolution will be substantially uniform with the movement of 90 the sheet of glass.

I have found, however, that with the varying conditions, such as occur when sheets of different thickness and different degrees of temperature, &c., are drawn, there is an occasional relative movement between the surface of the roller and of the sheet of glass if reliance is placed entirely upon the frictional contact of the sheet with the roller to drive the latter. I have therefore devised means whereby power may be 95 applied to the shaft of the bending-roller, which power, however, just falls short of being sufficient to impart revolution to the roller. This is accomplished, for example, by means of a friction-clutch interposed between the driving-shaft and the roller-shaft, in which the friction is adjusted to such a point that the clutch will slip and fail to drive the roller, but is nevertheless so great that with very slight additional power applied the roller will readily revolve. This additional power is supplied by the frictional contact of the sheet of glass with the roller. By this means the greater portion of the power necessary to drive the roller is obtained from a suitable source of power, and reliance is placed upon the sheet merely to add the overbalancing amount necessary to produce the revolution.

Finally, the invention consists in certain 125 detailed methods of procedure and constructions of apparatus, which will be hereinafter more fully described and then pointed out in the claims.

It will be apparent to those expert in the art 130

that the inventive ideas hereinbefore described are capable of finding expression in methods varying somewhat in detail and that the inventive idea involved in the mechanism is capable of receiving a variety of mechanical expressions. In the accompanying drawings, for the purpose of illustration only, I have disclosed one form of apparatus which may be employed; but such illustration is not to be regarded as defining the limits of the invention, reference being had to the claims for that purpose.

In said drawings, Figure 1 is a broken detailed perspective view of apparatus employed in practicing the invention, and Fig. 2 is a detailed view illustrating a slightly-modified method of procedure. Fig. 3 is a side elevation of the machine, illustrating the means of applying power to the various parts of the apparatus. Fig. 4 is a central vertical longitudinal section of the apparatus. Fig. 5 is an elevational view of the side opposite to that shown in Fig. 3. Fig. 6 is a vertical transverse section on the line 6-6, Fig. 4. Fig. 7 is a broken plan view, partly in section, of that portion of the apparatus lying immediately over and contiguous to the working chamber or pot. Fig. 8 is a sectional detail illustrating a portion of the apparatus for driving the bending-roll.

In the drawings like reference-numerals indicate like parts, and referring to Figs. 4 and 6, 1 is a melting chamber or furnace of any suitable or usual construction, and 2 is a working chamber or pot in communication therewith through a suitable opening or openings 3, provided in the lower portion of a bridge-wall 4. Preferably there are two openings 3, one on each side of the working chamber or pot, so that the glass passing from the melting-furnace 1 will enter the working chamber 2 adjacent to or beneath the edges of the sheet being drawn. Any suitable or usual means for heating the working chamber or pot 2 may be employed, and as the specific construction of such means does not form any essential part of the present invention the same are not shown in the drawings. Mounted within the confines of the working chamber 2 are a pair of oppositely-disposed rollers 5, composed of any suitable refractory material, such as a suitable clay. These rollers are mounted upon substantially parallel hollow shafts 7, (best shown in Figs. 1 and 4,) which shafts have their bearings upon the exterior of the working chamber, the shafts extending through the walls of said chamber, as shown in Fig. 7. The bearings of these shafts are arranged so that the shafts may be each adjusted at each end both in a vertical and horizontal direction. Preferably there are mounted on the supporting structure of the machine suitable frames 8, Fig. 5, arranged to slide horizontally on a suitable bearing plate or plates

9. Screw-shafts 10, one for each frame, are mounted to turn in bearings on plate 9, but without longitudinal movement with relation to said bearings, such movement being restrained, as by a collar 11 or other suitable means. These screws 10 engage corresponding female threads on the frames 8 and may be revolved by any suitable means, the direction of movement of the frames depending upon the direction in which the screws are turned, as will be readily understood. Sliding vertically within the frames 8 are bearing-boxes 12, and projecting vertically upward from said boxes are screws 13, which pass through the top portion of the frames 8 and are engaged by nuts bearing upon the top of the frames and having hand-wheels 14 rigidly secured thereto, so that by revolving the hand-wheels the bearing-boxes may be elevated or depressed. Each of the shafts 7 has an enlarged bearing-surface 15, (see Fig. 1,) corresponding in shape to a portion of a sphere, which rests in a corresponding bearing in boxes 8, which boxes are constructed in two parts in order to admit of the assembly of the elements. This form of bearing is one well known in mechanics and provides for the proper horizontal and vertical adjustment of the shafts one at a time and independently at each end of each shaft without imparting any strain to the parts, and also permitting of easy movement, even though the adjustments at each end of either shaft may not be absolutely identical.

For the purpose of preventing the shafts 7 from becoming unduly heated by the intense heat to which they are subjected within the working chamber 2, these shafts, as before stated, are hollow, as plainly indicated in Fig. 4, and water is circulated through the shafts, the same being conducted into the shafts through flexible couplings 15', Fig. 1, and emerging through couplings 16.

The mounting of the refractory rollers 5 with relation to the mass of molten glass in the working chamber is such that the lower peripheries of the rollers are more or less immersed within the surface of the molten glass, and these rollers are driven at the same rate of speed, but in opposite directions, the direction of revolution of the two rollers preferably being such that their adjacent surfaces move upward, as indicated by the arrows in Fig. 1. Any suitable mechanism for thus driving the two rollers in opposite directions, but at the same rate of speed, may be employed. As here shown, (see Figs. 3 and 6,) each of the shafts is provided with a sprocket-wheel 17. Power drawn from any source is conveyed by variable-speed connections, as a friction-cone 18, to a shaft 19, having thereon a worm 20, engaging a worm-gear 21 on shaft 22. Shaft 22 carries a gear 23 keyed thereto and a sprocket-wheel 24. Gear 23 meshes with a gear 25 keyed to a

shaft 26, which shaft carries a sprocket-gear 27 of the same dimensions as the sprocket-gear 24 on the shaft 22. It will thus be seen that the two shafts 22 and 26 are driven in opposite directions, and that therefore the sprocket-wheels on these shafts turn in opposite directions. A sprocket-chain 28 passes from sprocket-wheel 24 over sprocket-wheel 17 on one of the shafts 7 and a sprocket-chain 29 passes over the sprocket-wheel 27 and the sprocket-wheel 17 on the other shaft 7. Since the sprocket-wheels 17 are alike in dimensions and the sprocket-wheels 24 and 27 are also alike in dimensions, it follows that the two rollers 5 will not only be driven in opposite directions, but at the same rate of speed.

Mounted between the rollers 5 and in position adjacent to the edges of the sheet that is to be drawn are the devices for holding the sheet to uniform width and preventing the narrowing tendency heretofore mentioned. Any suitable means for this purpose will be within the scope of the present invention; but as here shown such means consist of hooks 30 of refractory material immersed in the molten mass of glass adjacent to the edges of the sheet being drawn, said hooks being provided with means for manipulating them so as to impart movement to the molten mass adjacent to the edges of the sheet away from the medial line of the sheet and toward its edges. The hooks are clamped on the ends of levers 31, Fig. 6, pivoted at 32 to swinging links 33. By grasping the handle ends of the two levers 31 they may be manipulated in such a way as to cause the hooks to dip into the molten mass of glass and move a slight distance toward the medial line of the sheet, after which they can be slightly raised and then drawn outward toward the edges of the sheet, thereby imparting movement to the surface portion of the molten mass toward the edges of the sheet, and thus operate to hold the sheet to its uniform width. If desired, these hooks may be operated automatically instead of by hand, as shown and described in the aforementioned application, Serial No. 304,555.

As illustrated in Fig. 4, the receptacle 2 is covered over, except for a narrow slot or opening through which the sheet of glass 33 is drawn. The cover portion of the receptacle is preferably provided with downwardly-extending lip portions 34, whose lower lines preferably are below the plane of the upper sides of the rollers 5, which rollers are placed beneath and a little bit to one side of said lips 34. The object of these downwardly-extending lips is to assist in preventing the heated gases of combustion which are directed against the molten glass on and to the rear of the rollers from passing over the rollers and injuriously affecting the sheet of glass being drawn. In addition to these

downwardly-extending lips two shields 35 35 are provided, which shields are supported on either side of the sheet of glass being drawn and parallel therewith and between the rollers 5 and said sheet. The heated gases of combustion which pass over the rollers 5 and under the lips 34 34, as well as the intense heat radiated from the molten glass carried up by the rollers 5, would so melt down or soften the sheet of glass being drawn as to either make it draw very thin or would render the drawing of the same entirely impracticable, and the shields 35 35 are therefore supplied to protect the sheet of glass at the point immediately above where it is drawn from the destructive influences of the gases of combustion and the heat radiated from the rollers. These shields are preferably in the form of flat hollow chambers and are provided with means for circulating a cooling medium, as water, therethrough, water being supplied, for example, through pipes 36 and carried off by pipes 37, a suitable flexible hose 38 being attached to the said pipes for the purpose of induction and education of the water. These shields 35 35 are not for the purpose of cooling either the sheet of glass being drawn or the surface of the molten glass lying between the rollers. In fact, care must be exercised to avoid any material cooling of the surface of the molten mass by the action of these shields, since if any appreciable cooling due to this cause takes place it is liable to materially affect the successful drawing of the sheet. In other words, the elements 35 35 are provided as shields, and shields only, to protect the sheet of glass from radiated heat from the rollers and the gases of combustion passing over said rollers. For the purpose of placing said shields at the proper distance above the molten mass to effectually perform their office as shields and yet at the same time provide against placing them so near the molten mass as to exercise an appreciable cooling effect thereon these shields are so mounted that they may be adjusted both in a vertical and a horizontal direction. One very simple means for this purpose consists in resting the pipes 36 37, which support the shields, upon bricks or other refractory material 39, Fig. 4. The shields may be readily adjusted toward or from the sheet of glass along the top of these refractory bricks, and their height may be adjusted by using a greater or less number of bricks under the supporting-pipes 36 37.

Any suitable means may be employed for supplying the heat necessary to superheat the surface of the molten glass in the working chamber 2 to the rear of the rollers 5. As here shown, that portion of the molten mass lying to the rear of the roller 5 nearest to the melting-furnace 1 is superheated by permitting the heated gases of combustion to pass from the melting-furnace 1 over the top of

the bridge-wall 4 against the roller, and then to pass upward and outward through suitable flues, as indicated by the arrows, and into the downwardly-leading stack 40. (Indicated by dotted lines in Fig. 4.) The means for superheating the glass to the rear of the other roller, as here shown, consist of burners 41, Fig. 1, located in a chamber adjacent to the working chamber 2, and provided with a flue 42, through which the gases of combustion are conducted to the rear of the roller 5, after which they are conducted by return-flues to the downwardly-leading flue 43, and hence to a suitable stack 44.

Referring to Figs. 1, 3, 4, and 8, 45 is a bending-roller located in heated chamber 46 and carried on a shaft 47, whose ends extend through the walls of the chamber 46 and are carried on suitable antifrictional bearings located in bearing-boxes 48. The shaft 47 is hollow and is provided with suitable means for conducting a cooling medium therethrough—for example, the pipe 49, Fig. 1, leading from a source of water-supply and a suitable corresponding pipe at the opposite end leading to the sewer or other waste. Secured to the shaft 47 is a sprocket-wheel, over which a sprocket-chain 50 passes as well as around a second sprocket-wheel 51 on a shaft turning in bearings 52, which latter shaft has keyed thereto a worm-gear 53, which is engaged by a worm 54 on shaft 55, turning in bearings 56 and having keyed thereto friction-disks 57 and 58. The disk 57 is fixed on the shaft and the disk 58 is free to slide longitudinally thereon, but compelled, like disk 57, to revolve therewith. Mounted loosely on the shaft 55, between the disks 57 and 58, is a sprocket-wheel 59, over which passes sprocket-chain 60, leading to the driving-shaft 19. Bearing on the disk 57 is spring 61, which reacts between said disk and the flange 62 on a nut 63, threaded on the outer end of the shaft 55 and provided with a hand-wheel 64. By turning the hand-wheel 64 in the proper direction the spring 61 may be compressed, and hence the disk 58 forced so as to grip the sprocket-wheel 59 with increased friction between the two disks 57 and 58.

By reference to Fig. 1 it will be seen that the shaft 47 of the bending-roller is provided with a hand-wheel 65.

It will be readily seen that by adjusting the friction of the disks 57 and 58 upon the sprocket-wheel 59 the same may be brought to a point where the friction will be just below the point necessary to drive or revolve the bending-roller 45, the friction-disks slipping on the surface of the sprocket-wheel 59. By feeling of the hand-wheel 65 and by the addition of a very slight amount of power by hand to revolve the same the operator can ascertain when the friction of the disks 57 and 58 on the sprocket-wheel 59 has reached

the point where a slight additional amount of power will be sufficient to revolve the bending-roller. It being known in advance what additional power will be furnished by the sheet of glass as it passes over the bending-roller the mechanism is so adjusted that this additional amount of power will be sufficient to revolve the roller in unison with the movements of the sheet. The best results are obtained with this friction-clutch device when the disks 57 and 58 are revolving much more rapidly than it is desired to turn the bending-roller 45, so that even when the friction is sufficient in combination with the action of the sheet of glass to revolve the roller the friction-disks 57 and 58 will be slipping upon the sprocket-wheel 59.

When warming up the machine previous to beginning the operation of drawing a sheet of glass, the disks 57 and 58 are pressed with sufficient friction against the sprocket-wheel 59 to alone turn the bending-roller 45, and when the machine is ready for the drawing to begin the friction is eased through the hand-wheel 64 until the friction will be just below the point necessary to drive the bending-roller, the action of the sheet passing therover being sufficient to furnish the additional power required.

In order to avoid the tendency of the molten glass to pile up at the ends of the rollers 55 and around the shafts thereof, which tendency if continued might result in a clogging action between the ends of the rollers and the walls of the working chamber, I provide burners 66, which pass through the walls of the working chamber, preferably at a point immediately below where the shafts of the rollers pass through said walls, said burners being connected with the gas system by means of suitable piping 67. (See Figs. 1 and 3.)

Immediately to the rear of the drawing-chamber 46 is a leer 68, and at the point where said leer joins the drawing-chamber 46 there is a removable door or closure 69. Mounted on the rear of the drawing-chamber 46 is a drum operated by suitable power mechanism, and around this drum is wound chain 70, carrying the bait 71 employed in starting the operation.

Any suitable apparatus for continuously drawing the sheet of glass may be employed, that herein shown consisting of an endless carrier 72, coacting with grip-bars 73, supported on endless chains 74, which elements act not only to continuously draw the sheet of glass, but to advance it through the heating-chamber 46 and into the leer 68. As these last-described elements form no material or essential part of the present invention they need not be more fully described. As here shown, they are substantially those shown in the previous applications above mentioned.

For the purpose of enabling the bait 71 to be passed from the rear end of the drawing-chamber 46 between the carrier and the grip-bars over the bending-roller and down into the melting chamber or pot between the rollers 5 5 and the shields 35 35 it is necessary that means should be provided for temporarily raising the grip-bars out of contact with the carrier. Such means are clearly shown in Fig. 3, in which 75 75 are the shafts which carry the sprocket-wheels over which the chains bearing the grip-bars pass and by which said chains are driven. These shafts 75 rest in bearing-boxes 76 on the exterior of the drawing-chamber, which boxes are supported on substantially horizontal rods 77, having one end pivoted to the framework of the machine at 78 and having the other end pivoted at 79 to spring-links 80, carried on crank-arms 81, keyed to shafts 82, to which latter shafts are keyed worm-wheels 83, engaged by worms 84 on shaft 85, to which is keyed a hand-wheel 86.

By turning hand-wheel 86 the operator may revolve the crank-shafts 82, and thereby elevate the links 80, and with them the shafts 75, thus lifting the grip-bars free from the carrier, and the closure 69 being removed bait 71 may be passed downward into the leer and forward through the heating-chamber 46, over the bending-roller 45, and down into the working chamber 2 between the shields 35 35, and the drum carrying the chains 70 being set in motion by suitable power; as by the sprocket-chain 87, Fig. 5, leading to the source of power, the bait is drawn upward over the bending-roller through the heating-chamber 46 between the carrier 72 and the grip-bars 73 and out of the rear end of the heating-chamber, where it is detached from the sheet of glass in any suitable manner, as by cracking the glass from the bait or separating the bait from the chains 70. At this point the hand-wheel 86 is operated to lower the grip-bars 73 into contact with the sheet of glass, and said sheet being gripped between the bars and the carrier and power being applied the sheet of glass is thereafter continuously pulled upward over the bending-roller and advanced by the grip-bars through the leer 68 over the antifrictional bearings 88.

By inspection of Fig. 4 it will be seen that each transverse bar of the carrier 72 will travel faster as it passes around the sprocket-wheels supporting the carrier than it will during the time when it is traveling between the supporting sprocket-wheels, and hence if the bars between the sprocket-wheels are moving at the same rate of speed as the sheet of glass, as they must, the bars passing around the front sprocket-wheel and coming up into position to receive the glass as it comes from the bending-roller will be moving slightly faster than the glass. Now it is essential

that the several bars constituting the carrier (during the time when they are in contact with the sheet of glass) should travel at the same rate of speed as the glass, in order that there may be no relative movement between the sheet and the carrier, since such movement would result in a marring of the fire-finish of the sheet. I have found that if the bending-roller 45 be placed with its upper surface or highermost point on a level with the upper part of the carrier the bar 72', Fig. 4, of the carrier will come in contact with the sheet of glass at a time when it is moving slightly faster than the sheet, and is therefore liable to, and sometimes does, slightly mar the fire-finish of the sheet by reason of the rubbing action that takes place just as the sheet comes in contact with the bar 72'. For the purpose of making it impossible for the sheet of glass to contact with the bar 72' until said bar has reached its highermost position—that is, a position immediately over the driving-shaft—I mount the bending-roller 45 in such a position that the highermost part of the roller will be above the level of the carrier, so that the sheet gradually descends from the top of the roller onto the carrier, as clearly shown in Fig. 4. By this means I insure the contact of the sheet of glass and the carrier at the time, and only at the time, when said carrier and sheet are moving at the same rate of speed.

As shown in all the figures except Fig. 2, the refractory rollers 5 5 move in the direction indicated by the arrows in Fig. 1—that is, with their adjacent surfaces moving upward and then outward. This is the preferred direction of movement; but it is not essential, since in some cases the rollers 5 5 may move in the reverse direction—that is, with their adjacent surfaces moving downward and outward, as indicated by the arrows in Fig. 2.

It will be understood that all the shafts of the rollers 5 5, the bending-roller 45, the shafts supporting the carrier, and grip-bars are made hollow and are connected by suitable stuffing-boxes with conduits, which conduct a suitable cooling fluid, as water, into the hollow pipes, suitable eduction or exit pipes being provided on the opposite ends. By this means injury to the shafts of the several parts by the intense heat of the machine is avoided.

While for the purpose of convenience in illustration I have shown the rollers 5 5, the friction-clutch mechanism for the bending-roller 45, and the worm-shaft 90 for driving the mechanism in the drawing-chamber as all having power directly from the shaft 19, it will be readily understood that I may and sometimes do interpose variable speed mechanism between said shaft 19 and rollers 5 5 and the friction-clutch mechanism for the bending-roller, to the end that the speed of these elements may be adjusted to secure

the best results. Of course it is entirely possible to so proportion the parts to the shaft 19 as shown in Fig. 3; but in many instances the introduction of variable-speed mechanism is preferable.

5 It will be seen from the foregoing that I have provided an exceedingly simple method and apparatus whereby a continuous sheet of glass may be drawn from a mass of molten glass, the width of the sheet maintained substantially uniform, and the appearance on the surfaces of the drawn sheet of ribs or striæ avoided, as well as any marring effects of the fire-finish due to a rubbing action of 15 the several parts upon the surface of the glass.

It will of course be understood that parts of the described mechanism may be employed without other parts and that therefore my invention is not limited to the use of all the parts described and operating as a whole. Moreover, it will be readily comprehended by those familiar with this art that many changes in the form, location, and 25 relative arrangement of the various elements described may be made without departure from the spirit of my invention.

Having thus described my invention, what I claim is—

30 1. The method of drawing sheet-glass which consists in preparing a mass of molten glass, drawing a sheet of glass therefrom and simultaneously imparting movement to a part of the surface of the molten glass in opposite directions and away from the two faces of the sheet.

2. The method of drawing sheet-glass which consists in preparing a mass of molten glass, drawing a sheet of glass therefrom and 40 simultaneously imparting movement to a part of the surface of the molten glass away from each face and also away from each edge of the sheet.

3. The method of drawing sheet-glass which consists in continuously drawing a 45 sheet of glass from a mass of molten glass, and continuously moving a portion of the surface of the molten mass away from the two faces of the sheet as drawn.

50 4. The method of drawing sheet-glass, which consists in continuously drawing a sheet of glass from a mass of molten glass, and continuously moving a portion of the surface of the molten mass away from the 55 two faces and the two edges of the sheet as drawn.

5. The method of drawing sheet-glass, which consists in continuously drawing a sheet of glass from a mass of molten glass, 60 continuously replenishing the supply of molten glass as the drawing proceeds, and continuously moving a portion of the surface of the molten mass away from the two faces and the two edges of the sheet as drawn.

65 6. The method of drawing sheet-glass,

which consists in drawing a sheet of glass from a mass of molten glass, and continuously submerging the surface portion of the molten mass on each side of the sheet being drawn.

70 7. The method of drawing sheet-glass which consists in preparing a mass of molten glass, superheating a portion of the surface of said molten mass, shielding a portion of said surface from said superheating effect, 75 drawing a sheet of glass from said shielded portion and simultaneously causing a part of the same shielded surface to move in opposite directions and away from the faces of the sheet being drawn.

80 8. The method of drawing sheet-glass which consists in preparing a mass of molten glass, superheating a portion of the surface of said mass, shielding a portion of said surface from said superheating effect, drawing a 85 sheet of glass from said shielded portion, causing the surface to move outward or in a direction away from the center toward the edges of the sheet, and simultaneously causing part of the surface of the molten mass opposite the faces of the sheet to move away 90 from said faces.

9. The method of drawing sheet-glass which consists in preparing a mass of molten glass, heating a portion of the surface above 95 the point which it should have for drawing into sheet form, separating a portion of said surface and subjecting it to the action of the atmosphere whereby its temperature is lowered, drawing a sheet of glass from said separated portion, and imparting movement to 100 part of the surface of said separated portion away from the faces of the sheet.

10. The method of drawing sheet-glass which consists in preparing a mass of molten 105 glass, superheating a portion of the surface thereof, subjecting another portion of the surface of said molten mass to the cooling action of the atmosphere, drawing a sheet of glass from said last-named portion, moving a 110 part of said cooled surface away from the faces of the sheet being drawn and returning it to said superheated area.

11. The method of drawing sheet-glass which consists in preparing a mass of molten 115 glass, superheating two parts of the area of the surface of said mass, slowly submerging and advancing said superheated portions to an intermediate area exposed to the cooling influence of the atmosphere and drawing a 120 sheet of glass from said intermediate area.

12. The method of drawing sheet-glass which consists in preparing a mass of molten 125 glass, superheating two parts of the area of the surface of said mass, slowly submerging and advancing said superheated portions to an intermediate area exposed to the cooling influence of the atmosphere, drawing a sheet of glass from said intermediate area and simultaneously moving parts of the surface of 130

said intermediate area away from the faces of the sheet being drawn and returning them to said superheated areas.

13. In a machine for drawing sheet-glass, 5 the combination of a receptacle containing molten glass, means for drawing a sheet of glass therefrom, and means simultaneously imparting movement to parts of the surface portion of the molten mass away from the 10 two faces of the sheet as it is drawn.

14. In a machine for drawing sheet-glass, the combination of a receptacle containing molten glass, means for drawing a sheet of glass therefrom, and means simultaneously 15 imparting movement to parts of the surface portion of the molten mass away from each face and each edge of the sheet as it is drawn.

15. In a machine for drawing sheet-glass, the combination of a receptacle containing 20 molten glass, two parallel rollers revoluble in opposite directions with the lower part of their peripheries immersed in the molten glass, and means for drawing a sheet of glass from the molten mass between said rollers.

25 16. In a machine for drawing sheet-glass, the combination of a receptacle containing molten glass, two parallel rollers revoluble in opposite directions with their adjacent surfaces moving upward and the lower part 30 of their peripheries immersed in the molten glass, whereby a portion of the mass of molten glass is carried over and outward by said rollers, means for revolving both of said rollers at the same speed, and means for drawing 35 a sheet of glass from the mass of glass between said rollers.

17. In a machine for drawing sheet-glass, the combination of a receptacle containing molten glass, two parallel rollers revoluble in 40 opposite directions with their adjacent surfaces moving upward and the lower part of their peripheries immersed in the molten glass, means for revolving said rollers, means for adjusting the rollers toward and from 45 each other, and means for drawing a sheet of glass from the molten mass between said rollers.

18. In a machine for drawing sheet-glass, the combination of a receptacle containing 50 molten glass, two parallel revolving rollers with their adjacent surfaces moving upward and the lower part of their peripheries immersed in the molten glass, means supplying heat to the rear sides of said rollers, and 55 means drawing a sheet of glass from the molten mass between said rollers.

19. In a machine for drawing sheet-glass, the combination of a receptacle containing molten glass, two parallel revolving rollers 60 with their adjacent surfaces moving upward and the lower part of their peripheries immersed in the molten glass, means drawing a sheet of glass from the molten mass between said rollers, means supplying heat to the rear

sides of the rollers, and means protecting the 65 sheet from said heat.

20. In a machine for drawing sheet-glass, the combination of a receptacle containing molten glass, two parallel revolving rollers with the lower part of their peripheries immersed in the molten glass, means for vertically and horizontally adjusting said rollers, 70 and means for drawing a sheet of glass from the molten mass between said rollers.

21. In a machine for drawing sheet-glass, 75 the combination of a receptacle containing a mass of molten glass, means for drawing a sheet of glass of uniform width therefrom, a roller over which said sheet is bent as drawn, and power devices tending to but falling 80 short of revolving said roller, the frictional contact of the sheet with the roller supplying the additional power necessary to revolve the roller.

22. In a machine for drawing sheet-glass, 85 the combination of a receptacle containing a mass of molten glass, means for drawing a sheet of glass of uniform width therefrom, and a bending-roller driven by the combined action of power devices and the friction of 90 said sheet as it is bent over said roller.

23. In a machine for drawing sheet-glass, the combination of a receptacle containing a mass of molten glass, means for drawing a sheet of glass of uniform width therefrom, a 95 roller over which said sheet is bent as drawn, power devices tending to revolve said roller, and a slip connection between said devices and roller.

24. In a machine for drawing sheet-glass, 100 the combination of a receptacle containing a mass of molten glass, means for drawing a sheet of glass of uniform width therefrom, a roller over which said sheet is bent as drawn, power connections tending to revolve said 105 roller, and a friction-clutch interposed in said connections.

25. In a machine for drawing sheet-glass, the combination of a receptacle containing a mass of molten glass, means for drawing a 110 sheet of uniform width therefrom, a roller over which said sheet is bent as drawn, a lever device attached to the shaft of said roller, power devices tending to revolve said roller, and yielding connections between said power 115 devices and said roller.

26. In a machine for drawing sheet-glass, the combination of a receptacle containing a mass of molten glass, means for drawing a sheet of uniform width therefrom, a roller over which said sheet is bent as drawn, a hand-wheel attached to the shaft of said roller, power devices tending to revolve said 120 roller, and yielding connections between said power devices and said roller.

27. In a machine for drawing sheet-glass, the combination of a receptacle containing a mass of molten glass, means for drawing a

sheet of glass of uniform width therefrom, power devices, and a roller over which said sheet is bent as drawn and receiving driving power from the sheet and from said power devices.

28. In a machine for drawing sheet-glass, the combination of a receptacle containing a mass of molten glass, means for drawing a sheet of glass therefrom, means imparting movement to parts of the surface portion of the molten mass away from each face of the sheet as it is drawn, and a roller over which said sheet is bent as drawn and receiving driving power from the sheet.

29. In a machine for drawing sheet-glass, the combination of a receptacle containing a mass of molten glass, means for drawing a sheet of glass therefrom, means imparting movement to parts of the surface portion of the molten mass away from each face of the sheet as it is drawn, power devices, and a roller over which said sheet is bent as drawn and receiving driving power from said sheet and from said power devices.

30. In a machine for drawing sheet-glass, the combination of a receptacle containing a mass of molten glass, two parallel rollers having a portion of their peripheries immersed in said molten mass, means for drawing a sheet of glass from the molten mass between said rollers, and a roller over which said sheet is bent as drawn and receiving driving power from said sheet.

31. In a machine for drawing sheet-glass, the combination of a receptacle containing a mass of molten glass, means for drawing a sheet of glass of uniform width therefrom, a roller over which said sheet is bent as drawn, and a sheet-receiving carrier moving in a plane below the top line of said roller.

32. In a machine for drawing sheet-glass, the combination of a receptacle containing a mass of molten glass, means for continuously drawing a sheet of glass of uniform width therefrom, a roller over which said sheet is bent as drawn, and a continuously-moving sheet-receiving carrier in a plane below the top line of said roller.

33. In a machine for drawing sheet-glass, the combination of a receptacle containing a mass of molten glass, two parallel rollers revolving in opposite directions with a portion of their peripheries immersed in said mass, means for drawing a sheet of glass from the mass between said rollers, means directing a high heat against the rear sides of said rollers, and means shielding the sheet of glass from said heat.

34. In a machine for drawing sheet-glass,

the combination of a receptacle containing a mass of molten glass, two parallel rollers revolving in opposite directions with their peripheries immersed in said mass, means for drawing a sheet of glass from the mass between said rollers, means conducting hot products of combustion against the rear sides of said rollers, means to the rear of said rollers conducting said products to a suitable outlet-flue, and means shielding the sheet of glass from the heat of said products of combustion.

35. In a machine for drawing sheet-glass, the combination of a receptacle containing a mass of molten glass, a pair of refractory rollers revolving with a portion of their peripheries immersed in said molten mass, means directing a cooling fluid through the shafts of said rollers, and means drawing a sheet of glass from said molten mass.

36. In a machine for drawing sheet-glass, the combination of a receptacle for molten glass, two parallel rollers mounted with the lower part of their peripheries in the molten glass, means for drawing a sheet of glass of uniform width from the molten glass between said rollers, two hollow shields mounted above said molten glass, one between each roller and the sheet being drawn, and means for circulating a cooling medium through said shields.

37. In a machine for drawing sheet-glass, the combination of a receptacle containing a mass of molten glass, means for drawing a sheet of glass of uniform width from said glass, two rollers mounted one on each side of the said sheet with their peripheries dipping in said molten glass and their shafts projecting outward through the walls of said receptacle, and means supplying a high temperature in said receptacle adjacent to the ends of said rollers.

38. In a machine for drawing sheet-glass, the combination of a receptacle containing a mass of molten glass, means drawing a sheet of uniform width from said mass, two rollers mounted on hollow shafts and with their peripheries dipping into said molten mass on each side of said sheet, means directing a cooling medium through said shafts, and burners directing a jet of flame into said receptacle adjacent to the ends of said rollers.

In testimony whereof I have signed this specification in the presence of two subscribing witnesses.

IRVING W. COLBURN.
